UNITED STATES PATENT OFFICE.

THOMAS S. CLOGSTON, OF BOSTON, ASSIGNOR TO HIMSELF AND HORACE P. WAKEFIELD, OF READING, MASSACHUSETTS.

IMPROVEMENT IN KITCHEN-RANGES.

Specification forming part of Letters Patent No. 34,121, dated January 7, 1862.

To all whom it may concern:

Be it known that I, THOMAS S. CLOGSTON, of Boston, in the county of Suffolk and State of Massachusetts, have invented certain Improvements in Kitchen-Ranges; and I hereby declare the following to be a full and sufficient description, reference being had to the accompanying drawings and references marked thereon.

The invention consists in the arrangement and combination, first, of the fire-box with the water-legs of the boiler; second, of the water-legs of the boiler with the ovens and smoke-flues; third, an arrangement of the auxiliary boilers over the main boiler, and, fourth, the arrangement and use of an oscillating grate made of tubes to be used as a substitute for the usual water-back.

The drawings for illustrating the invention embrace the figures following, namely:

Figure 1 is a front elevation of the range; Fig. 2, a top view of the whole apparatus set up; Fig. 3, a vertical view of the range, the top plate of the boiler with its steam-chambers and the two auxiliary boilers being removed; Fig. 4, a perspective view of the range and showing how water-fountains may be used; Fig. 5, a plan view of the oscillating grate; Figs. 6 and 7, different views of the parts for operating the grate.

This range is designed to be fitted up in brick-work in an ordinary kitchen fire-place or elsewhere. It is of a cubical form, as seen in Fig. 4, and is surmounted at top by two auxiliary boilers C².

A represents the fire-box; A', the brick-work; B, the ovens, one on each side of the fire-box; C, the lower portion of the boiler; C', the steam-chambers of boiler, and C² the auxiliary boilers resting on the steam-chambers, and the bottoms of which project downward into said chambers, which are rapidly heated thereby.

If we remove the upper part of the boiler on the line y y of Fig. 1 and look down on the lower half of the boiler, we have the view shown in Fig. 3, where the water of the boiler covers more than one-half of the fire-box and the entire top of each oven. Letters g represent the boundaries of said boiler on the sides covering the whole surface except the space occupied by the boiler-holes d d.

Letters h h represent the water-legs of the boiler, which legs extend to the bottom of the ovens B B, covering three sides of the two ovens and three sides of the fire-box, said legs interposing between said fire-box and ovens to equalize the heat of the ovens, and at the same time protect the metal of the fire-box from burning by undue heat.

Letter c is the direct flue to the chimney-pipe. c' and c² are side flues leading from fire-box A horizontally over ovens, then down flues a' vertically to the bottom of the ovens, and thence under the water-legs h h and outside of the boiler to flues c³, following the track of the arrows to the chimney-flue c⁴.

d d represent boiler-holes and cooking-spaces; e, rear boiler-space, all being placed over the fire-box.

The dotted lines seen in Fig. 3 between the fire-box and the ovens represent the continuous outline of the water-legs, where the view is obstructed by the top plate, which covers the front boiler-space and the passage of the side flues from the front boiler-spaces d d over the ovens.

A in Fig. 3 represents the whole area of the fire-box, and B B of the same figure the area of the oven-tops.

Letter a represents the handle of the damper, which opens and closes the descending flues a' a' under the ovens. The handles being turned outward open the flues, and turned inward close the same.

Letter a² shows the damper of the direct flue c, which being opened throws the whole draft from the fire-box through c to the chimney; but on opening damper under a' and closing that of a² the draft is carried over and behind and around outside of the ovens to flue c¹.

By inspecting Fig. 2 in detail we perceive the character of the auxiliary boilers with the steam-discharging pipes b b' projecting behind the auxiliary boilers from the steam-chambers c', b' indicating a weighted cap adapted to a certain amount of pressure in proportion to the strength of the boiler. One of the boilers C² has a projecting bottom i i, (seen in dotted lines of Fig. 1,) by means of which the auxiliary boiler is conveniently and quickly heated to a certain temperature, but never to the same extent as the main boilers

C. The remaining boiler C², not having the projecting bottom i i, will not be heated to the same extent, and may serve where merely warm water is required.

The tops or covers of the auxiliary boilers are hinged in the usual way, and raised and lowered by handles f f.

The fire-box in its individual character presents no particular qualities, and requires no special description.

The fire-grate and its accompanying apparatus have peculiarities which require particular description.

The grate is designed for oscillatory movement. An end view of it is shown in dotted lines in Fig. 1, A³, and a sectional plan view detached in Fig. 5; also in Figs. 6 and 7 are separate views of detached parts. Fig. 4 shows the arrangement of pipes in dotted lines provided for supplying the grate with cold water from an elevated cistern D', and the hot-water cistern D² is for receiving the water that has passed through the grate. They only show a suitable arrangement that might be used for operating hot water.

The grate is composed of a series of parallel tubes (letters r) opening into hollow end pieces (letters o) communicating with the hollow shaft k l, while k k represent the bearings of the shaft in place. There are openings n through the cross-piece P communicating freely with shaft k l when the cross-piece lies as shown in Fig. 5. Said opening n is seen where it passes through the shaft in Fig. 6. Said cross-piece is capable of rotating on the shaft in the same manner as a stop-cock might be rotated on its plug. If the grate be stationary and the cross-piece P be rotated a quarter of a circle, the communication between it and the fountains will be closed off, and if the rotation be continued onward another quarter of a circle the communication is again open, as before.

In the center of the oscillatory shaft and parallel with its axis is inserted a thin plate or diaphragm of metal m m, extending from the end l and extending to the farthest side of the nearest end piece of the grate. The flat face of this diaphragm m is shown in Fig. 7. The edge view of it is shown in Figs. 5 and 6. The purpose of the diaphragm is that the water designed to circulate through the grate on entering P in the direction of the arrow and through the first half of the grate, which is on the entering side, passes through the outer half of the grate, which is on the exit side, and thence passes out of piece P to the hot-water reservoir or fountain, fol-

lowing arrows t t'. Thus by a suitable arrangement of the fountain for cold water above and hot water below a circulation may be established, acting in the same general manner as a water-back with similarly-situated hot and cold water reservoirs. For example, we may place a fountain at the highest elevation D' and a similar one D² at a lower level at such relative elevations that the longer column of the one will constantly tend to discharge through the grates A³ and into the hot-water reservoir D²; but I do not claim the relative arrangement of these two reservoirs, as that is well understood. As the grate is described as an oscillating grate, and as the part P is made to rotate on the shaft of the grate and while the grate is in its normal or horizontal position, the cross-piece P must also be horizontal to keep up the circulation. To secure these objects, the piece P is made stationary, while the grate is left to oscillate on its axis. This movement is performed by the application of a suitable wrench to the hexagonal nut D, and is used for the purpose of stirring the fire on the grate; or the grate may be slightly inclined, and this will contract the opening and diminish the circulation.

Having stated the character of the invention and described and explained the construction of the apparatus, what I claim as my invention, and desire to secure by Letters Patent, is—

1. The combination of a cubical fire-box with the three water-legs of the boiler in contact with the three surfaces of the said fire-box, as described, so that two of said water-legs shall be interposed between the fire and the ovens to moderate the heat thereof, substantially as set forth.

2. The arrangement and combination of an oven between three water-legs of the boiler on three of its sides, while the two flues from the fire-box pass over the top of said oven, and thence down its farthest side to the bottom of the water-legs, and thence around by the outside and to the rear, substantially as described.

3. The oscillating tubular grate in kitchen-ranges constructed and operating substantially as set forth.

4. The combination of the stationary part P with the oscillating grate, substantially as set forth.

THOMAS S. CLOGSTON.
